UNITED STATES PATENT OFFICE.

NEM WILLIAM BRANNON, OF GREER, SOUTH CAROLINA, ASSIGNOR TO DRAPER CORPORATION, OF HOPEDALE, MASSACHUSETTS, A CORPORATION OF MAINE.

AUTOMATICALLY-THREADING SHUTTLE FOR LOOMS.

Application filed October 30, 1925. Serial No. 65,880.

To all whom it may concern:

Be it known that I, NEM WILLIAM BRANNON, a citizen of the United States, and a resident of Greer, in the county of Greenville and State of South Carolina, have invented an Improvement in Automatically-Threaded Shuttles for Looms, of which the following description, in connection with the accompanying drawings, is a specification, like characters on the drawings representing like parts.

This invention relates to automatically threading shuttles and is more especially directed to the tension means for exerting proper tension on the thread during weaving.

It has heretofore been common to provide various means of shuttle tensions to insure laying the filling straight in the shed, and some of such tension devices have been made adjustable so that the tension on the thread may be varied from time to time in accordance with the character of the thread in use. In such cases, however, the adjustability of the tension device has not been readily accomplished and usually some tools or adjusting devices have been necessary in order to vary the tension exerted by the tension device.

One of the objects of the present invention is to provide a shuttle of the automatically replenishing type with a tension device which may be readily manipulated by the weaver to vary the tension either more or less without necessitating either removal of the tension device itself or the employment of any tools for the purpose.

In the illustrated form of the invention the shuttle is shown as provided with a threading block of the open type, such, for instance, as shown and described in the Edward S. Stimpson patent, No. 1,483,492, Feb. 12, 1924, wherein a thread casting device has been employed for casting the thread on the occurrence of a loop or overthrow, and while the advantages of the present invention are well manifested in connection with such character of shuttle and threading block, it is to be understood that applicant may employ the present invention in connection with other types of automatically threading shuttles.

The tension device of the present invention consists of a tension pad which as shown

has a laterally flaring opening for the entrance of the thread as it swirls or balloons on the first pick following replenishment and thereafter exerts tension upon the thread during weaving as the thread draws between the jaw members of the pad. In order that the tension may be varied from time to time in accordance with the character or kind of thread in use, a pad holder is provided which also has a lateral opening and an arm extending over one of the jaws of the pad and formed of a pliable, substantially non-elastic material or metal, which may be bent in different positions and when bent will retain its bent form to thereby vary the opening through which the thread passes during weaving and consequently the tension exerted upon the thread.

The invention and new combination of parts will best be made clear from the following description and the accompanying drawings of one good form thereof.

In the drawings:

Fig. 1 is a perspective view of the threading end of a loom shuttle provided with the present invention;

Fig. 2 is a longitudinal section of the threading end of the shuttle shown in Fig. 1;

Fig. 3 is an enlarged detached detail showing the tension device of the present invention detached;

Fig. 4 is an elevation of the tension device looking in the direction longitudinal of the shuttle and showing the tension pad with the jaw opening contracted for exerting increased tension upon the thread; and

Fig. 5 is a view similar to that of Fig. 4 showing the jaw opening of the pad enlarged to exert less tension upon the thread.

The loom shuttle 1 may be of usual character and formed of wood for the proper support of the filling carrier 2 on which the filling or thread 3 is wound, and as is common in filling replenishing shuttles the lower wall of the shuttle is cut away to provide an opening 4 for the discharge of the filling carrier.

Frontward of the bobbin chamber the shuttle is provided with a threading block 5 receiving chamber in which is secured the threading block 5 having a longitudinally extending thread passage 6, and laterally of

the longitudinally extending thread passage the shuttle is provided with the usual side delivery eye 7.

Frontward of the threading block 5 the shuttle wood is cut away as at 8 to provide a leader for the thread that it may pass into control of the threading block on the first pick following replenishment.

The threading block 5 is secured in the shuttle body by the usual cross-bolt 9 and as shown in the present instance, the pin 10 extends downwardly from the threading block and is received in an opening in the shuttle body. These parts may be of usual construction and as more particularly shown and described in the Stimpson patent, to which reference has hereinbefore been made. The longitudinally extending thread passage 6, when of the open top character, as indicated, has a thread casting device 11 which may be formed as a scroll of substantially the same general character as that which is more fully shown and described in the Stimpson patent, and if desired, the threading block 5 may be formed of cast iron having a rust-proof covering.

The tension device, in accordance with the present invention, is preferably located in the longitudinally extending thread passage and, as shown, is disposed between the threading block and the bobbin chamber.

The tension device comprises a tension pad and a tension pad holder, both of which are provided with an opening for the entrance of the thread into control of the tension device on the first pick of the shuttle following replenishment.

The tension pad 12 may be formed of yielding material, such as felt or the like, but is preferably (though not necessarily) formed of rubber, as shown, and comprises a block of the pad material having an opening 13 flaring transversely of the longitudinally extending thread passage. When the shuttle is threaded, the thread draws between the upper jaw 14 and the lower jaw 15 of the pad, with the result that if the upper and lower jaws are brought closer together and retained in such position, the tension on the thread will be greater than if they are further apart, a condition indicated in Figs. 4 and 5.

The tension pad 12 may be suitably shaped in accordance with the conditions of use, but as herein shown it is substantially of block form and the laterally extending jaw 14 has its outer surface bevelled or inclined as at 16, in order to more effectively direct the thread into control of the tension device, as the thread balloons from the bobbin on the first pick following replenishment.

The pad holder may be variously contrived, but one of the essential features thereof is that it be formed of a pliable or ductile material, such as lead, for instance,

which may be bent into different positions and when so bent retain its bent position.

The pad holder as shown in the drawings comprises a base portion 17 which may rest upon or in a groove formed in the bottom wall of the threading block receiving chamber, as indicated in Fig. 2, and such base portion 17 is provided with a downwardly extending finger 18 that projects into a cut-away or rabbeted portion 19 formed in the shuttle wood and preferably in the recess which receives the bolt 10 of the threading block. The base portion 17 is of sufficient length to enable the pad holder portion proper of the holder to be located between the threading block and bobbin chamber and, as herein shown, the pad holder has upwardly projecting portions 20, 21 and 22 which engage the lower or base portion of the pad, and the upwardly projecting portion 23 preferably formed at the side of the pad remote from the mouth or opening 13, and such upwardly projecting portion 23 has an arm 24 which overlies the upper jaw 14 of the pad, the construction being such that the arm 24 which is formed of pliable and substantially non-elastic material as described, may be bent either downwardly or upwardly, and when so bent, the arm 24 will retain its bent position to define the size or character of the thread engaging opening of the pad. As shown in Fig. 4, the arm 24 has been bent downwardly, with the result that the upper jaw 14 of the pad has been moved towards the lower jaw 15 and the mouth 13 of the pad has been correspondingly contracted to exert considerable tension upon the thread *a*, which, as above stated, passes between the jaws of the pad.

In Fig. 5 the opposite condition has been brought about; that is, the arm or plate 24 overlying the upper jaw 14 of the pad has been bent upwardly, as compared with the position of parts in Fig. 4, with the result that the jaws 14 and 15 of the pad have been separated and the mouth 13 of the opening has been correspondingly enlarged to thereby vary the tension upon the thread.

When the weaver wishes to increase the tension upon the thread in use, he simply presses downwardly upon the plate or arm 24 of the pad holder, and such pressure may be conveniently exerted by the finger of the weaver. On the other hand, should the weaver desire to decrease the tension on the thread, he has only to lift or bend the arm or plate 24 upwardly, as indicated in Fig. 5, it being understood that the pliable and substantially nonelastic character of the arm or plate 24 permits such ready bending by the finger of the weaver, and, when bent, the arm retains the position to which it has been moved.

From the construction described, it will be clearly apparent that the pad being

formed of resilient material, such, for instance, as rubber or felt, and the pad holder or essential feature thereof, that is, the overlying arm or plate 24, being formed of substantially non-resilient material which may be bent into desired shape, and retain the bent form, the weaver can at once adjust the tension of the pad to suit the condition or character of the yarn in use without de-
10 lay and without the use of special tools.

What is claimed is:

1. An automatically threading loom shuttle having a threading block provided with an open top thread passage and a side delivery eye, a tension pad having a thread receiving opening with a flaring mouth, and a tension pad holder having a part enclosing one of the jaws of the flaring mouth of the tension pad formed of a pliable sub-
20 stantially inelastic metal that may be bent into different positions and retain its bent form to vary the size of the thread receiving opening and the tension exerted upon the thread during weaving.
2. An automatically threading loom shuttle having a threading block provided with a longitudinally extending thread passage, a side delivery eye, a thread tension device having a pad with a mouth flaring laterally of the thread passage and an arm overlying the upper jaw of the flaring mouth and formed of pliable substantially inelastic material that may be bent up or down and retain its bent position to vary the tension exerted upon the thread during weaving.
3. An automatically threading loom shuttle having a threading block with a longitudinally extending thread passage and side delivery eye, a tension device comprising a tension pad having a lateral opening for receiving the thread, and a pad holder also having a lateral opening, and one arm overlying one jaw of the tension pad opening and secured to the shuttle body.
4. In an automatically threading shuttle for looms, the combination of the shuttle body having a threading block provided

with a longitudinally extending thread passage and a side delivery eye, and a tension device comprising a friction pad having a thread receiving opening and a pad holder formed of a pliable substantially inelastic metal which may be bent into different pad holding positions and retain its bent form to vary the size of the thread receiving opening in the pad and the consequent amount of tension exerted on the thread passing therethrough.

5. An automatically threading loom shuttle having a threading block and a side delivery eye, a thread tensioning pad having an opening through which the thread passes during weaving, and a pad holder formed of pliable substantially inelastic material having a bendable portion bearing upon the pad at one side of the opening for varying the size of said opening and the consequent tension exerted upon the thread.

6. An automatically threading loom shuttle having a threading block and a side delivery eye, a thread tensioning pad having an opening through which the thread passes during weaving and located between the threading block and bobbin chamber, and a pad holder formed of pliable substantially inelastic material having a bendable portion bearing upon the pad at one side of the opening for varying the size of said opening and the consequent tension exerted upon the thread.

7. An automatically threading loom shuttle having a threading block and side delivery eye, and a thread tension device comprising a rubber pad having jaws for receiving the thread, and a pad holder secured to the shuttle body and having a part overlying a jaw of the rubber pad formed of pliable substantially nonelastic metal that may be bent in the shuttle and retain its bent form to vary the tension exerted upon the thread during weaving.

In testimony whereof, I have signed my name to this specification.

NEM WILLIAM BRANNON.
